UNITED STATES PATENT OFFICE.

EDWARD BLAISE, OF BROOKLYN, NEW YORK.

CABINET FOR TALKING-MACHINE RECORDS.

1,334,945.

Specification of Letters Patent.

Patented Mar. 30, 1920.

Application filed November 15, 1918. Serial No. 338,340.

To all whom it may concern:

Be it known that I, EDWARD BLAISE, a citizen of the United States, and resident of the borough of Brooklyn, in the city and State of New York, have invented a new and useful Improvement in Cabinets for Talking-Machine Records, of which the following is a specification.

This invention relates to a cabinet for talking machine records, and has for an object to provide such a structure which includes means for very compactly holding a large number of records when out of use and for simply and quickly exposing the said records for separate withdrawal for use.

Another object consists in providing such a structure in which the records are held when out of use in flat horizontal position, and in substantial parallelism with each other; while the said records are positively presented for withdrawal in substantially vertical position and fan-like arrangement.

Another object consists in providing such a structure which is relatively cheap and simple to manufacture, easy to operate and sightly in appearance.

A further object consists in providing certain improvements in the form, construction and arrangement of the several parts, whereby the above named and other objects may be effectively attained.

A practical embodiment of my invention is represented in the accompanying drawings, in which—

Figure 1 represents a detail face view of the cabinet showing record holding elements in open and closed positions.

Fig. 2 represents a horizontal section, partly broken away, taken in the plane of the line II—II of Fig. 1, looking in the direction of the arrows.

Fig. 3 represents a detail section taken in the plane of the line III—III of Fig. 1, looking in the direction of the arrows, parts being shown in different positions in full and dotted lines.

Fig. 4 represents a detail section taken in the plane of the line IV of Fig. 3, looking in the direction of the arrow, and

Fig. 5 represents a detail section taken in the plane of the line V of Fig. 3, looking in the direction of the arrow.

The structure includes an outer casing which has a rear wall 1 and side walls 2, 3; the said casing being designed to support and inclose a number of drawer-like ele-

ments which incorporate my invention. On the insides of the walls 2, 3 slats 4, 5 are secured in spaced relation by screws 6, these slats being horizontally disposed and serving as tracks for the drawer-like elements so that, as will be understood, the said elements will thus be arranged in a vertical series in the casing. The casing may be of such size as to accommodate any desired or convenient number of the said elements; and, as the elements are identical, it will be sufficient to give a detail description of but one.

I have referred to these elements as being drawer-like, because they are adapted to be slid in and out of the casing like drawers, and each of the said elements includes a member which I call the drawer and a member which I call the receptacle.

The drawer is composed of side members 7, 8 and a rear member 9. Upper longitudinal members 10, 10* are secured to the tops of the side members and lower longitudinal members 11, 12 are secured to the bottoms of the side members. Cross bars 13, 14 are also provided running beneath and secured to the lower longitudinal members 11, 12. The arrangement of the said parts is clearly shown in the drawing and it will be understood that they may be secured together in any desired manner so as to constitute a drawer of skeleton formation. Since the cross bars 13, 14 lie in a plane below the lower longitudinal members 11, 12 they are fitted to rest and travel upon the slats 4, 5 secured to the inner side walls of the casing; and it will be observed that the side members 7, 8 are cut away so as to accommodate the slats 4, 5 and thereby enable each drawer to lie in close contact with the adjacent drawers in order to economize space.

The front of the casing 1, 2, 3 has a series of cross pieces 15 that are horizontally arranged and let into notches 16 formed in the sides 2 and 3 so as to be flush with the front thereof. These cross pieces are so arranged that one will lie between each pair of drawers and they are located in the same planes as the cross bars 13, 14 of the drawers and held in place by moldings 17, 18. The result of this arrangement is that, when a drawer is pulled forward on the slats 4, 5 its outward movement will be terminated by the contact of its cross bar 14 with a cross piece 15, as clearly shown in Fig. 3. The said cross bar and cross piece are so located as to be in abutment when the drawer pro-

trudes a little more than half its length from the casing.

The receptacle comprises a front member 19, side members 20, 21 and end members 22, 23. The end members 22, 23 are flanged and secured to the front member 19 by screws 24. The other extremities of the end members are perforated to receive screws 25, 26 that are fitted in the side members 7, 8 of the drawer. As a result of this arrangement it will be seen that the receptacle is pivoted to the drawer. The side members 20, 21 are provided at their lower corners with clips 27 that carry trunnions 29, which enter complementary apertures in the end members 22, 23, thus providing an articulated receptacle which has the capacity of opening in a fan-like manner. The front member 19 of the receptacle may be composed of wood, like the drawer and casing, but the side members may conveniently be composed of some fibrous material, such as binder's board, and the end members 22, 23 of sheet metal.

The edges of the side members 20, 21 are provided at points located from the clips 27 a distance about equal to the length of the end members 22, 23 with additional clips 30 connected by strengthening bands 30*, that also carry trunnions 31 fitted to enter grooves 32, 33 fashioned in the inner faces of the side members 7, 8 of the drawer. It will be observed that the clips 30 on the side member 21 are slightly farther away from the front member 19 than are the clips 30 on the side member 20, see Fig. 3. The shape of the grooves 32, 33 is clearly shown in this same figure and it will be observed that they are curved and that each one has a slight almost straight extension at one end; this extension being at the upper part of the grooves entered by the trunnions 31 on the side member 20 and at the lower part of the grooves entered by the trunnions 31 on the side member 21. These grooves lie on each side of the pivot point formed by the screws 25, 26 and are eccentric to an imaginary circle struck with the said screws as its center. The said grooves may be conveniently formed by screwing or otherwise fastening properly shaped ribs or cleats 34, 35 to the inner faces of the side members 7, 8, and it will be seen that the screws 25, 26 serve as this fastening means in part.

The size and shape of the front member 19 of the receptacle corresponds substantially with the cross sectional size and shape of its drawer and, by reference to Fig. 3, it will be seen that the extremities of the straight portions of the grooves 32, 33 are, in the case of each pair of said grooves, separated by a distance substantially equal to the height of the front member 19; while the opposite extremities of each pair of said grooves are much farther apart. This ar-

angement insures that when the trunnions 31 are at the extremities of the straight portions of the said grooves, the side members 20, 21 will be in substantial parallelism with each other and sufficiently close together to enable the receptacle to be housed within the drawer. On the other hand, when the trunnions 31 are in the opposite ends of the said grooves, the side members 20, 21 are spread apart so as to cause the receptacle to assume a fan-like shape.

From the foregoing description it will be seen that when the receptacle is swung about the pivots 25, 26 until its end members 22, 23 are substantially parallel with the side members 7, 8 of the drawer, the receptacle will be housed within the drawer as shown in dotted lines, Fig. 3. This movement of the receptacle will cause the trunnions 31 on the side members 20, 21 to travel to and be seated in the extremities of the straight portions of the grooves 32, 33; this motion being effected by the eccentric formation of the said grooves. By pushing the drawer inwardly into the casing 1, 2, 3, the receptacle will be caused to retain this position owing to the engagement of the side members 20, 21 with the adjacent drawers. This is shown in the lower part of Fig. 3. As soon, however, as the drawer is pulled out to the position shown in the upper part of Fig. 3, the receptacle will, when released, automatically swing down from the dotted position into a position substantially at right angles to the drawer (shown in full lines, Fig. 3) and this movement will, owing to the eccentricity of the grooves 32, 33, cause the trunnions 31 to travel to the opposite ends of said grooves and thereby positively and automatically open the receptacle into fan-like shape. Thus it is only necessary for the user to seize the handle or knob 36 on the front member 19 and pull the drawer and receptacle outwardly from the casing until the cross bar 14 engages its complementary cross piece 15 and then let go of the said knob, in order to open the drawer and receptacle for withdrawal of the records. In returning the parts to closed position it is simply necessary to grip the knob 36, swing the receptacle up into the dotted position shown in Fig. 3, and then force the drawer and receptacle inwardly until housed by the casing. The cross plate 37 which is secured to the bottom of the drawer serves to limit the downward movement of the side 20 of the receptacle and to also hold the same against warping when housed within the drawer. Thus the records are kept compactly and yet may be exposed for convenient examination and withdrawal.

It will be understood that the receptacle 19-23 is intended to hold the talking machine records, which latter will be incased in a suitable envelop designed for the purpose.

Various changes may be resorted to in the form, construction and arrangement of the several parts, without departing from the spirit and scope of my invention; and 5 hence I do not intend to be limited to the details herein shown and described except as they may be included in the claims.

What I claim is:

1. Apparatus of the character described 10 comprising, a drawer and an articulated receptacle fitted to be carried by the drawer in closed position and in substantial parallelism therewith, and to be also carried by the drawer in open position and substantially at right angles thereto, said receptacle having a three point connection with the drawer for positively controlling the position of the receptacle.

2. Apparatus of the character described 20 comprising, a drawer and an articulated receptacle fitted to be carried by the drawer in closed position and in substantial parallelism therewith, and to be also carried by the drawer in open position and substantially at right angles thereto, said receptacle being pivoted to swing from the one position to the other and having its sides connected to the drawer so as to cause them to separate when the receptacle is swung downwardly and approach each other when the receptacle is swung upwardly.

3. Apparatus of the character described 30 comprising, a drawer and an articulated receptacle fitted to be carried by the drawer in closed position and in substantial parallelism therewith, and to be also carried by the drawer in open position and substantially at right angles thereto, said receptacle being pivoted to swing from the one position to the other and having its sides connected to the structure by pin and slot connections so as to cause the sides to separate when the receptacle is swung downwardly and to approach each other when the receptacle is swung upwardly.

4. Apparatus of the character described 40 comprising, a drawer and an articulated receptacle fitted to be carried by the drawer in closed position and in substantial parallelism therewith, and to be also carried by the drawer in open position and substantially at right angles thereto, said receptacle being pivoted to swing from the one position to the other and having its sides provided with trunnions, and grooves fashioned in the sides of the drawer at each side of the point at which the receptacle is pivoted, said grooves being eccentric to an imaginary circle struck with said pivot point as

its center, whereby the sides of the receptacle are caused to separate when the receptacle is swung downwardly and to approach each other when the receptacle is swung upwardly.

5. Apparatus of the character described 60 comprising, a drawer and an articulated receptacle fitted to be carried by the drawer in closed position and in substantial parallelism therewith, and to be also carried by the drawer in open position and substantially at right angles thereto, said receptacle being pivoted to swing from the one position to the other and having its sides provided with trunnions, and grooves fashioned in the sides of the drawer at each side of the point at which the receptacle is pivoted, said grooves being eccentric to an imaginary circle struck with said pivot point as 70 its center and each having a straight portion at one extremity.

6. Apparatus of the character described 80 comprising, a drawer and an articulated receptacle fitted to be carried by the drawer in closed position and in substantial parallelism therewith, and to be also carried by the drawer in open position and substantially at right angles thereto, said receptacle having a front member, side members and end members, the end members being pivoted to the drawer to permit the receptacle 90 to swing from the one position to the other and the side members being connected to the drawer so as to cause them to separate when the receptacle is swung downwardly and to approach each other when the receptacle is swung upwardly.

7. Apparatus of the character described 95 comprising, a drawer and an articulated receptacle fitted to be carried by the drawer in closed position and in substantial parallelism therewith, and to be also carried by the drawer in open position and substantially at right angles thereto, said receptacle having a front member, side members and end members, the end members being pivoted to the drawer to permit the receptacle 100 to swing from the one position to the other and the side members being connected to the drawer so as to cause them to separate when the receptacle is swung downwardly 105 and to approach each other when the receptacle is swung upwardly, said side members being pivoted to said end members.

In testimony, that I claim the foregoing as my invention, I have signed my name this 110 fourteenth day of November, 1919.

EDWARD BLAISE.
